UNITED STATES PATENT OFFICE.

CARL W. WEISS, OF NEW YORK, N. Y., ASSIGNOR OF ONE-HALF TO AUGUST MIETZ, OF NEW YORK, N. Y.

GOVERNOR FOR HYDROCARBON-ENGINES.

SPECIFICATION forming part of Letters Patent No. 723,957, dated March 31, 1903.

Application filed August 13, 1900. Serial No. 26,714. (No model.)

To all whom it may concern:

Be it known that I, CARL W. WEISS, a citizen of the United States, residing in the borough of Manhattan, in the city, county, and 5 State of New York, have invented certain new and useful Improvements in Governors for Hydrocarbon-Engines, of which the following is a specification, reference being had to the accompanying drawings, forming a part hereof.

10 This invention relates to governors for hydrocarbon-engines whereby the speed of the engine controls the delivery of oil to form the basis of the explosive charge. In common with other governing devices of this type an 15 eccentric or cam is operatively connected with the plunger of the pump which supplies the charge of oil to the cylinder, the position of such eccentric or cam being shifted with variations in the speed of the rotating part; but, 20 unlike the previous devices, the transmission mechanism between the eccentric and the plunger is so arranged as to give a quick hammer-like blow to the plunger. Heretofore the eccentric-strap has been connected 25 positively with the plunger, giving to the latter a gradual movement. In the present invention the plunger is operated with a hammer-like blow, which causes the oil to be injected quickly and forcibly; so that it is completely and instantly vaporized in the cylinder, to the great improvement of the action 30 of the engine.

The invention will be more fully described hereinafter with reference to the accompanying drawings, in which—

Figure 1 is a plan view of a hydrocarbon-engine equipped with the improved governor, some parts being broken out and shown in section to illustrate details of construction. 40 Fig. 2 is a detail view in section on the plane indicated by the broken line 2 2 of Fig. 1, on a slightly larger scale; and Fig. 3 is a detail plan view of the parts shown in Fig. 2.

In the engine chosen for illustration of the 45 application of the invention the cylinder A is represented as provided with an extension or crank-chamber A², in the walls of which the crank-shaft C has its bearings. Upon the crank-shaft or upon the hub of one of the fly- 50 wheels C' is pivotally mounted a weight C² to swing toward or from the axis of the crank-

shaft, being held normally toward the axis by a spring C³. The pivoted weight or weighted arm C² is provided with a short arm or link c² for the purpose of connecting the same 55 operatively with an eccentric D. The latter has an elongated opening d to receive the shaft C to permit the eccentric to be moved transversely with respect to the shaft to decrease or increase its eccentricity as the 60 weight or weighted arm C² moves farther away from or toward the axis of the shaft with the increase or decrease in the speed of rotation, the eccentric being compelled to rotate with the shaft through its connection 65 with the weight or weighted arm C² and the connection of the latter with the shaft or with the fly-wheel secured thereon. An eccentric-strap E embraces the eccentric and is connected by a rod E' in the construction shown 70 in the drawings with one arm F of a bell-crank lever, which is suitably supported on the engine, the other arm F' carrying a roller f' to strike against the end of a reciprocating rod F², which in turn operates the plunger of 75 a pump G, which supplies oil to the working cylinder to form the basis of the explosive charge, the plunger being returned by the action of a spring.

It will be seen that with every change in 80 the speed of rotation of the shaft C, no matter how slight, the throw of the eccentric, and consequently the effective movement of the pump-plunger, will vary accordingly, so that the quantity of oil fed to the cylinder will be 85 varied in exact accordance with the requirements of the varying conditions of load under which the engine is operated, and, furthermore, the throw of the eccentric being greater than the stroke of the plunger, which is operated by contact only, the plunger will not follow the gradual movement of the eccentric, but will be operated with a quick hammer-like blow and will inject the oil forcibly and at the proper instant.

As a detail of construction which may be employed to advantage in connection with the governor mechanism already described for convenience in starting and in stopping engines of the type referred to the contact 90 rod F², which slides freely in its support on the engine and is held against the arm F' by

the action of the spring *g*, surrounding the plunger of the pump, which bears against said rod, has secured thereto a pin or projection *h* in the path of a pin or projection *h'* on a lever *H*, which is pivoted on the engine. In starting the engine the lever *H* is manipulated to throw forward the rod *F*², and consequently the plunger of the pump, thereby forcing into the cylinder of the engine a sufficient quantity of oil to form the basis of the first explosive charge. For the purpose of stopping the engine a sliding latch *I* is mounted in the support of the rod *F*² to be pushed into engagement with a notch *i* in the rod *F*² when it is desired to stop the engine. The notch *i* is so placed on the rod *F*² as to be engaged by the latch when the rod is at or near its extreme forward point, whereby the plunger of the pump is held in its forward position against the action of the spring *g*.

I claim as my invention--

The combination with a hydrocarbon-en-

gine having a pump to deliver oil directly to the cylinder or explosion-chamber, of an eccentric mounted to move transversely with 25 respect to the axis of the engine-shaft, a weight pivotally mounted upon said shaft and connected to said eccentric to shift the same as the speed of the engine varies, and operative connections between said eccentric and the 30 plunger of said pump, said connections including a part moved by the eccentric with a throw greater than the stroke of the plunger and operating the plunger, by contact, with a hammer-like blow to inject the oil forcibly 35 and instantly, substantially as shown and described.

This specification signed and witnessed this 9th day of August, A. D. 1900.

CARL W. WEISS.
